STRUCTURE

Thomas Maddock, Phoenix, Ariz.

Application March 6, 1939, Serial No. 260,075

5 Claims. (Cl. 14—16)

The improvement relates to span structures.

The object of the improvement is to reduce the weight and cost of structures.

Expansion and contraction are provided for in 5 continuous spans of all kinds in order to reduce thrusts on columns and piers, to utilize the advantages of continuous spans of unlimited length and to increase the rigidity of spans.

Provision is made to equate the maximum positive 10 and negative moments in I beams and to create initial stress in girders, beams and trusses combining expansion, continuity and moment stress control.

Figure 1 is a side elevation of a multiple span 15 I beam.

Figure 2 is an enlargement of the device permitting expansion while retaining continuity.

Figure 3 is an adjustable hanger.

Figure 4 is an adjustable pin seat. 20 Figure 1 shows a terminal span 7 with one free and one fixed end, a span 8 with fixed ends, containing the expanding device and part of span 9 which is similar to span 8. The piers or supports are designated at 10—11 and 12.

Figure 2 shows one method of constructing the 25 device which consists of two hangers, 5 and 6, connected by pins 1, 2, 3 and 4 to the two I beams which are reinforced by the two bars, 20 and 21, for bending and pin bearing. The reverse side 30 of the beam is likewise equipped with bars and hangers to give double shear on pins and central loading.

Expansion is provided by the rotation of hangers while the horizontal separation of the two 35 hangers prevents the rotation of one beam about the pin of the other, as with a single hanger, thus resisting bending moments.

With given loads and location of device the 40 moment stress on pins and hangers depends upon the horizontal distance between pins 1 and 3, etc.

Shear is carried by one or both hangers, the amount depending upon the loading and the location of the device between piers 11 and 12.

45 The longer the hangers between pins 1 and 2, etc., the less is the angle of hanger inclination from vertical at maximum and minimum temperatures and the resulting end thrust in beams. This end thrust is a percentage of the shear stress 50 as moment stress in the two hangers is opposite and cancels.

It is well known that on uniformly loaded continuous beams that below the yield point the stresses over supports equal

55 $\frac{WL}{12}$

and at center of spans

60 $\frac{WL}{24}$

and that beyond the yield point both these stresses tend to equalize at

5 $\frac{WL}{16}$ This equalization of stresses is secured below the yield point when a simple span is loaded uniformly to $\frac{1}{4}$ of its ultimate load, then connected over supports to make a continuous structure, and the remaining $\frac{3}{4}$ of load applied. When the entire load is removed initial moment stresses remain in the span that are available to equate future moment stresses.

This initial stress is likewise secured by varying the elevation of the beams support.

Similar results with expanding continuous structures are secured, for instance, in span 8 with hanger 5, located at .1464L from pier 11, connecting the beams, the application of a uniform dead load results in equal moment stresses 20 at span center and support. When hanger 6 is then connected continuity is provided for the live loads. By selecting the position of the hangers and the preliminary loading before the second hanger is connected the desired initial moment stress is secured and the location of the points 25 of contra flexure in the spans under various loads is controlled.

Figure 3 shows one type of adjustable hanger composed of bearings 13, 14 and 15, two rods, 16, with left and right hand screw threads and 30 nuts, 17 and 18, which can be used to create the initial stress desired in the beam.

Figure 4 shows an adjustable pin seat with split bearing, 24, and shims, 23. In lieu of preliminary loading to provide initial moment stress one 35 hanger, as 5, may be connected and 6 adjusted to position by jacks before being connected. Hangers or pin bearings may be adjustable to secure pre-stress and, to provide for wear or pier settlement.

In design of multiple continuous beams by reducing the length of the end spans, etc., varying the elevation of the end supports and pre-stressing the internal spans practically equal positive and negative maximum moments in all the spans 45 is secured for dead and live loading.

The drawing shows device as applied to I beams but it is also applied to girders, trusses, concrete beams and spans in general.

As a modification of two horizontally separated 50 hangers, sliding hangers, sliding plates or rollers to transfer both shear and positive or negative moments across expansion joints are similarly used to secure expansion, continuity and control of moment forces. Spans 8 and 9, etc., are stable 55 as simple beams except for a small horizontal force when hangers are inclined.

I claim:

1. A device in spans of internal expanding 60

- structures consisting of two hangers connecting the members, said hangers being separated horizontally to resist moment stresses in addition to carrying shear stresses.
5. 2. A device in spans of internal expanding structures consisting of two hangers connecting the members, said hangers being adjustable to create initial stress or to make corrections for pier settlement.
10. 3. A device in spans of internal expanding structures consisting of two sets of bearings between members and said bearings being separated horizontally to resist moment stresses in addition to carrying shear stresses.
15. 4. A device in spans of internal expanding

structures consisting of two sets of bearings between members said bearings being separated horizontally to resist moment stresses in addition to carrying shear stresses and being adjustable vertically to create initial stress or to make 5 corrections for pier settlement.

5. The art of securing minimum stresses or maximum economy in continuous structures, consisting of pre-loading or pre-stressing simple or cantilever spans to secure initial stresses and 10 the connecting by an internal expanding device of said spans or their members to form said continuous structures.

THOMAS MADDOCK. 15
